UNITED STATES PATENT OFFICE.

THOMAS HALLINAN, OF PATERSON, NEW JERSEY.

ELECTRICAL TOY GUN.

1,343,127.

Specification of Letters Patent.

Patented June 8, 1920.

Application filed March 3, 1919. Serial No. 280,393.

To all whom it may concern:

Be it known that I, THOMAS HALLINAN, a citizen of the United States, and a resident of Paterson, in the county of Passaic and 5 State of New Jersey, have invented a new and Improved Electrical Toy Gun, of which the following is a full, clear, and exact description.

This invention relates to electrical toys 10 and has for an object the provision of an improved construction wherein a number of shots may be fired from the same gun quickly under the power produced by an electromagnet.

15 Another object of the invention is the provision of a toy gun which will act in the nature of a rapid fire gun and which will successfully discharge missiles or projectiles as often, or substantially as often as the 20 switch can be opened and closed.

A still further object of the invention is to provide a small rapid fire gun electrically operated which will not readily get out of order and which may be easily manipulated 25 by a very small child without danger to the child or any of the surrounding objects.

In the accompanying drawing:

Figure 1 is a longitudinal vertical section through a toy gun disclosing an embodiment 30 of the invention.

Fig. 2 is a fragmentary sectional view through Fig. 1 on line 2—2.

Referring to the accompanying drawing by numerals, 1 indicates a block of wood or 35 other suitable foundation having an aperture in which the pin 2 is placed, said pin also fitting into a suitable aperture in the barrel 3 of the gun whereby said barrel may be swung around pivotally in order to shoot 40 in any direction. The barrel 3 is provided with a bore 4 which merges into a magazine opening 5 which is provided with a magazine 6 carrying a number of projectiles 7. These projectiles are fed automatically by 45 gravity into the breech of the bore 4 whereby they may be easily struck by the projecting anvil 8 of core 9, which is actuated by the solenoid 10. A spring 11 is used for moving the core back to its former position 50 as illustrated in Fig. 1 after each operation. The solenoid 10 is connected to a suitable source of current 12 by wires 13 and 14, wire 14 having a suitable switch 15 arranged therein, said switch being preferably in the 55 nature of an ordinary push button. By this construction and arrangement whenever the

switch 15 is closed solenoid 10 will become energized and will quickly draw in the core 9 against the action of spring 11. This movement will be sufficiently quick and 60 strong to cause a blow of the anvil 8 against the lowest projectile 7 so as to cause said projectile to move through the bore 4 out the muzzle 16 and for a suitable distance therebeyond. It is, of course, understood 65 that the strength of the current and the particular winding of the solenoid 10 are determining features which may vary the blow given by the anvil 8.

In operation, when the parts are arranged 70 as shown in Fig. 1 the closing of switch 15 will cause one projectile to be discharged. The various projectiles 7 are wood or some other non-magnetic material, while the core 9 is preferably of a good grade magnetic material so as to act quickly when the solenoid is energized. The core 9 will remain in its forward position notwithstanding 75 the action of spring 11 until the switch 15 is opened whereupon it will quickly move 80 rearwardly under the action of the spring ready for the second blow which will strike against the projectile, which by reason of gravity has by this time dropped into position in line with bore 4. 85

What I claim is:

1. A toy gun comprising a gun barrel pivotally mounted on a base so as to swing thereon, means for directing projectiles into the barrel, and a magnetic hammer for striking the projectiles and forcing them through 90 the bore of the barrel.

2. A toy gun comprising a barrel provided with a bore extending therethrough, a solenoid arranged in the rear part of the 95 barrel, a magnetic core positioned in said solenoid in line with said bore, and means for directing projectiles into said bore in line with said core so as to be struck thereby and projected through the bore and from 100 the barrel.

3. A toy gun comprising a barrel having a bore extending therein, means for directing projectiles to the breech end of the bore, a solenoid arranged adjacent the breech end 105 of the bore, a core positioned in the solenoid and provided with a projection acting as an anvil for striking the projectiles as they successively enter said bore so as to project them through the bore and through the muzzle of the gun, and means for returning the core to its starting point. 110

4. A toy gun comprising a barrel having a bore, a magazine projecting into said barrel near the breech end of the bore, said magazine being formed to guide under the action of gravity projectiles successively into the breech end of the bore, and a magnetic hammer positioned to strike the projectiles and force them through said bore and out the muzzle of the gun.
- 10 5. A toy gun comprising a barrel having a bore, a solenoid arranged adjacent the breech end of the bore, a magnetic core formed with a projection acting as an anvil for forcing projectiles through said bore and from the gun, a spring for returning said core to its starting point after each operation under the action of the magnetism of the solenoid, and a manually actuated

switch for closing the circuit of said solenoid for causing the actuation of said core. 2

6. A toy gun comprising a barrel having a projectile bore extending from the muzzle to near the breech and an enlarged bore at the breech, a solenoid fitted into said enlarged bore, a magazine for guiding projectiles into the projectile bore near the solenoid bore, a core arranged in the solenoid formed with a projection adapted to extend into the projectile bore and strike one of the projectiles fed therein by the magazine when the solenoid has been energized, a spring for returning the solenoid to an inoperative position, and means for supplying current to said solenoid, said means including a switch. 3

THOMAS HALLINAN.
